UNITED STATES PATENT OFFICE.

DANIEL J. MCPHERSON, OF CHERAW, SOUTH CAROLINA.

RAILROAD CROSS-TIE AND JOINT-CLAMP.

1,063,150.

Specification of Letters Patent. Patented May 27, 1913.

Application filed December 27, 1911. Serial No. 668,029.

To all whom it may concern:

Be it known that I, DANIEL J. MCPHERSON, a citizen of the United States, residing at Cheraw, in the county of Chesterfield and State of South Carolina, have invented a new and useful Improvement in Railroad Cross-Ties and Joint-Clamps, of which the following is a specification.

This invention relates to a railroad tie and joint clamp the object of the invention is to secure the rails upon both sides of the track in place by means of a single bolt to prevent spreading of the rails and also the longitudinal creeping of the tie, and a still further object of the invention is to utilize the principle of oppositely operating wedges for the purpose of forcing a movable portion of the clamping devices into engagement with the rails thus holding them firmly between said movable portions and fixed clamping members integral with the tie.

In carrying out the invention I employ the novel features of construction herein-after described, pointed out in the claims and shown in the accompanying drawings, in which:

Figure 1 is a side elevation of a tie with the clamping members, rails being shown in section. Fig. 2 is a plan view, the ball portions of the rails being partly broken away and the rail webs being shown in section. Fig. 3 is a section on the line 3—3 of Fig. 2. Fig. 4 is a fragmentary side elevation illustrating the construction of the clamping plates and operating wedges.

In these drawings 1 represents a metal tie having a flat upper surface upon which rest rails 2. This tie has its greater thickness midway its ends the under surface of the tie sloping upwardly from said central point to points adjacent the ends, which points are beyond the outer faces of the rails. The extreme end portions 3 of the tie are then angled and extend downwardly and outwardly, these end portions being the thinnest portions of the tie and practically forming end flanges extending obliquely with respect to the upper surfaces of the tie. This construction practically forms a cavity upon each side of the center of the tie in which

ballast or other suitable material may be packed and effectually prevents any longitudinal movement of the tie itself. At their inner ends the flanges 3 are carried inwardly to overhang the tie and are then bent upwardly thus forming an angled chair or locking plate 4 beneath which the outer base of the rail is adapted to fit and prevents any spreading of the rails in the direction of the flanges 3. Slidably mounted upon the tie are plates 5 which slide beneath suitable guide lugs 6 carried by the sides of the tie and each plate 5 has one end portion angled as shown at 7 to form a second chair or plate, the plates 7 engaging the inner sides of the rails and coöperating with the plates 4 for the purpose of holding the rails in position. In order to force the plates 5 toward the rails and lock them in position, each plate has its inner end longitudinally recessed and between these plates work substantial triangular shaped wedging blocks 8.

The sides of the wedge-shaped blocks which coöperate with the ends of the plates are rounded to fit the recesses in the ends of the plates. This serves to move the plates along the tie in a straight line without giving to them any vertical movement.

A bolt 9 passes through these blocks transversely to the tie upon which work suitable nuts 10. It is obvious that by tightening the nuts 10, the blocks 8 will be forced together thereby forcing the plates 2 apart and into engagement with the rails.

What I claim is:

1. A railroad tie having an integral rail engaging bridge and plates adapted to engage outer faces of parallel rails, inwardly extending lugs carried by opposite sides of the tie, plates slidably held beneath said lugs and adapted to engage the inner faces of the said rails, and oppositely movable wedge shaped blocks arranged between the end portions of the last mentioned plates and adapted to force them in opposite directions upon movement of said blocks toward each other.

2. A combined tie and rail chair comprising a base adapted to receive the rail and having a chair portion integral therewith,

said portion engaging the outer faces of parallel rails, movable chair members slidably held upon said base, each of said movable chair members having its inner end oppositely beveled, triangular blocks adapted to move transversely upon the base and arranged between said movable plates a bolt

extending through said blocks and transverse to the tie, and nuts working upon said bolt, as and for the purpose set forth.

DANIEL J. McPHERSON.
